CLAIM

The ornamental design for a docking station monitor stand, as shown and described.

DESCRIPTION

FIG. 1 is a front top perspective view of a docking station monitor stand showing our new design;

FIG. 2 is a rear bottom perspective view thereof;

FIG. 3 is a front bottom perspective view thereof;

FIG. 4 is a left side view thereof;

FIG. 5 is a right side view thereof;

FIG. 6 is a rear view thereof;

FIG. 7 is a front view thereof;

FIG. 8 is a top view thereof; and,

FIG. 9 is a bottom view thereof.

The broken lines shown in the drawings are included for the purpose of illustrating portions of the docking station monitor stand that form no part of the claimed design.
